UNITED STATES PATENT OFFICE.

DAVID B. WHISTLER, OF DAYTON, OHIO, ASSIGNOR TO THE RECORDING AND COMPUTING MACHINES COMPANY, OF DAYTON, OHIO, A CORPORATION OF OHIO.

OPERATING MECHANISM FOR FARE-RECORDERS.

1,169,447.

Specification of Letters Patent.

Patented Jan. 25, 1916.

Application filed March 17, 1913. Serial No. 754,634.

To all whom it may concern:

Be it known that I, DAVID B. WHISTLER, a citizen of the United States, residing at Dayton, in the county of Montgomery and State of Ohio, have invented certain new and useful Improvements in Operating Mechanism for Fare-Recorders, of which the following is a specification, reference being had therein to the accompanying drawing.

This invention relates to operating mechanism for fare recorders and the like and the object of the invention is to provide such an operating mechanism which will comprise a minimum number of parts; which will be very simple in its construction and operation and thus not liable to be rendered inoperative, due to the binding or disarrangement of the parts thereof; which will be of a strong, durable construction to enable it to withstand the severe usage to which it is subjected and which will be of such a character that it can be readily adapted for operation solely from the platforms or within the car.

In the accompanying drawings, Figure 1 is a top, plan view of a recorder and operating mechanism embodying my invention and showing the mechanism adapted for operation from a car platform; Fig. 2 is a section on the line $\alpha\alpha$ of Fig. 1 and looking in the direction of the arrows; Fig. 3 is an end elevation showing the actuating devices located upon the platform of a car; Fig. 4 is a side elevation of a portion of the mechanism embodying my invention showing the same adapted for operation from within the car; Fig. 5 is a section taken on the line $\gamma\gamma$ of Fig. 4, looking in the direction of the arrows and showing the actuating devices; Fig. 6 is a detail view of the connections between the operating rod and the setting and operating members carried by the recorder; and Fig. 7 is a plan view on a reduced scale of a recorder equipped with oscillating devices for imparting rotary movement to the actuating shaft.

In these drawings I have shown two embodiments of my invention as illustrating two of the various forms in which it may be applied, the essential features of both forms being the same. As shown in the drawings, the mechanism is mounted in a car, the end partitions of which are shown at 1 in Figs. 1 and 3 and the platform at 2 in Fig. 3.

Mounted within the car and preferably on one of the end walls 1 is a fare recorder 3 of a well known construction and adapted to classify and record fares of different kinds. To this end the recorder is here shown as comprising a setting member 4, which is rotated to set the operative parts of the recorder in a position to record a given fare, and also an operating member 5, by means of which the recorder is operated to cause said given fare to be recorded. This operating member preferably comprises a toothed rack 6 to operate suitable gearing to accomplish this function. As here shown the rack is a reciprocating rack and the operating member as a whole constitutes a slide bar but it will be understood that this operating member may be of any suitable character and that the toothed portion thereof may be in the form of a reciprocating rack or may be segmental in form and adapted to rock about a pivot in a well known manner. The setting and operating members of the recorder are connected by means of suitable connecting devices with the operating mechanism on the car which comprises a single operating rod 7 extending longitudinally of the car and capable of two distinct movements, in the present instance a reciprocatory movement and a rotary movement, and having connected therewith suitable devices for independently imparting thereto both of said movements. The connecting devices between this rod and the setting and operating members are such that the rotation of the operating rod to actuate the setting member will have no effect upon the operating member and likewise reciprocation of the operating rod to actuate the operating member of the recorder will have no effect upon the setting member. While these connections may be made in various ways I have in Figs. 1 and 2 shown the rod 7 provided with a gear 8 which is secured thereto and rotates therewith and which meshes with an elongated pinion 9 mounted on a stud shaft 10 carried in suitable bearings 11 of the bracket 15 and having thereon a bevel gear 12 which meshes with a bevel gear 13 carried by a shaft 14 mounted on a bracket 15 and forming an extension of the rotary setting member 4 to which it may be connected if desired by universal joints to permit of its being extended at an angle thereto. In this man-

ner the rotary movement of the shaft is imparted to the setting member of the recorder and the gear 8 will remain in mesh with the pinion 9 throughout the reciprocatory movement of the shaft, the pinion 9 being of a length sufficient to permit this. If desired, however, the gear carried by the shaft 7 may be splined thereto so that the shaft may move longitudinally relatively to the same. 5 Such a construction is shown in Figs. 4 and 6 where the shaft 7 is illustrated as having a bevel gear 16 splined thereto and held against longitudinal movement. The bevel gear 16 meshes with a corresponding gear 18 on a shaft 19 mounted in vertical bearings on a bracket 20 and having at its upper end a bevel gear 21 meshing with a similar gear 22 on the shaft 14 which, as above stated, forms an extension to the rotary setting member. In this instance the gear on the rod 7 remains stationary during the reciprocatory movement of that rod but is caused to rotate therewith.

As shown in Figs. 1 and 2 the connections 25 between the rod 7 and the operating member 5 of the recorder comprise a bell crank lever 23 pivotally mounted on an arm 24 of the supporting bracket and having one end connected to a link 25 which forms an extension to the slide bar 5 of the recorder, and having its other end in the form of a yoke embracing the rod 7 and having pins or trunnions 26 adapted to enter a grooved collar 27 rigidly secured to the shaft. In 30 this manner the reciprocatory movement of the shaft is transmitted to the operating member of the recorder and owing to the grooved collar and yoke connection the rotation of the rod 7 does not affect this connection.

The form of connection shown in Fig. 4 of the drawings is designed to connect the reciprocatory rod 7 with an oscillating operating member or shaft, as shown at 28. 45 The shaft 28 which may be either in one piece or in two parts, with a flexible connection, extends into the recorder and is connected with the operating mechanism thereof in a manner which is well known 50 and need not be here described. Suffice it to say that a rocking movement imparted to the shaft 28 by means of a segment 29 carried thereby will actuate the recording mechanism. To impart this rocking movement to the shaft 28 the segment 29 which is rigidly secured thereto meshes with the segment 30 pivotally mounted on the bracket 20 and having an arm 31 in the form of a yoke embracing the end of the 55 rod 7 and having pins which enter a grooved collar 32 rigidly secured to the rod so that the reciprocation thereof actuates the segments.

The two movements may be independently 60 imparted to the operating rod 7 in any

suitable manner. As above stated that form of the device shown in Figs. 1 to 3 is designed for operation from the car platform and the mechanism by means of which the rod is operated is mounted on the platform. 70 As here shown the rod 7 extends through both end partitions 1 of the car and each end is connected with a vertical rod 33 mounted upon the adjacent partition and capable of both a vertical, reciprocatory movement and a rocking movement about its longitudinal axis. The reciprocatory movement is preferably applied thereto by means of a foot pedal 34 mounted on the platform and connected with a rockshaft 35 carrying a crank 36 which is connected with the lower end of the vertical rod 33. 75 Rotary movement is preferably imparted to the rod by means of a handle 37 mounted on a short shaft 38 journaled in a bracket 39 and having secured thereto a segment 40 which meshes with a pinion 41 secured to the vertical rod 33, this pinion being of such a length that the vertical movement of the rod will not disengage it from the segment. 80 Inasmuch as the rod 7 is preferably arranged along one side of the car and the vertical rod 33 at a point near the doorway it is necessary to provide two means by which the two movements of the vertical rod can be transmitted to the horizontal rod. 85 To accomplish this a horizontal shaft 42 is rotatably and slidably mounted in brackets 43 carried by the partition and is connected at one end by means of a universal joint with a short shaft section 44 having a bevel gear 45 which meshes with a second bevel gear 46 secured to a shaft section 47 which is connected by means of a universal joint with the vertical rod 43. The two shaft 100 sections 44 and 47 are rotatably mounted in the arms of a Y-shaped bracket 48 pivotally mounted upon the bracket 43. The bearings in the bracket 43, through which the rods 33 and 42 extend, are of such a size as to 105 permit slight lateral play of their respective rods. The rod 42 has at its other end a short shaft section 49 connected to the rod 42 by a universal joint and provided with a bevel gear 50 meshing with a bevel gear 51 110 on a similar shaft section 52 connected by a universal joint with the rod 7, the shaft sections 49 and 52 being carried by a Y-shaped lever 53 pivotally mounted on a vertical axis on a bracket 54. By means of 115 this connection the reciprocatory movement of the rod 33 is transmitted to the rod 7 without disengaging the gears and the rotary movement is likewise imparted from the one rod to the other.

In that form of the device which is adapted to be manipulated from the inside of the car I have shown the rod 7 as provided with a hand grip 55, by means of 120 which it may be rotated and provided with 125

a drum-shaped portion having thereon a series of fare indications, as shown at 56, and coöperating with a pointer 57 carried by a fixed bracket adjacent to the handle 55 to indicate the position of the setting mechanism in the recorder. To impart longitudinal movement to the rod 7 a lever 58 is pivotally mounted at a point above the rod 7, as indicated at 59, and is connected with the rod 7 by means of a pin 60 extending into a grooved collar 61 rigidly secured to the shaft. The lower end or handle portion of the lever 58 extends downward to a point where it can be readily 15 grasped by the conductor or other operator. No claim is here made broadly to this particular mechanism, shown in Figs. 4 and 5, as a similar mechanism, embodying two rods, is shown and claimed in an application 20 for patent filed by me January 30th, 1913, Ser. No. 745,104.

It will be apparent from the foregoing description that I have provided an operating mechanism for fare recorders which 25 comprises a minimum number of parts and these parts being of such a character that they possess the strength necessary to withstand the severe and often rough usage to which they are subjected. Further, it is 30 apparent that the mechanism is of such a simple character that it cannot readily become disarranged or be rendered inoperative. Moreover, it will be apparent that in accomplishing this end I have provided a 35 single operating rod throughout the car, which rod is connected with the setting and operating members of the recorder.

While I have shown and described one embodiment of my invention it will be understood that this has been chosen for the 40 purpose of illustration only and that I do not desire to be limited to the details of construction shown and described, for obvious modifications will occur to a person skilled in the art.

Having thus fully described my invention, what I claim as new and desire to secure by Letters Patent, is:—

1. The combination, with a fare recorder 50 having a setting member and an operating member, both of said members having rotary movement, of a single actuating rod connected with both said setting member and said operating member and having two distinct movements, one of said movements being adapted to impart rotary movement to said setting member without affecting said operating member and the other of said movements being adapted to impart rotary 55 movement to said operating member without affecting said setting member.

2. The combination, with a fare recorder having a setting member and an operating member, both of said members having rotary movement and each of said members

having an extension projecting beyond the end of said recorder, of a single actuating rod, a gear connection between the extension of one of said members and said actuating rod, and a pivoted connection between 70 the extension to the other of said members and said rod, whereby the rotary movement of said rod will impart rotatory movement to one of said members and the reciprocatory movement of said rod will impart rotatory 75 movement to the other of said members.

3. The combination, with a fare recorder having both a setting member and an operating member, of a single rod having both a reciprocatory movement and a rotatory 80 movement, a connecting device connected with said rod and with one of said members, whereby the reciprocatory movement of said rod will impart movement to said member, a shaft journaled adjacent to said rod and having a gear, a gear carried by said rod and meshing with the gear on said shaft, a second gear on said shaft, and a gear connected with the other of said members and meshing with said second gear. 85

4. The combination, with a fare recorder having both a setting member and an operating member, of an operating rod having both a reciprocatory and a rotatory movement, a connecting device interposed between said rod and one of said members, a gear carried by said rod, a shaft journaled adjacent to said rod, a gear carried by said shaft and meshing with the gear on said rod, said rod having longitudinal movement relatively to 90 the gear on said shaft, and gearing connecting said shaft with the other of said members. 95

5. The combination, with a fare recorder having both a setting member and an operating member, of a single operating rod connected with both said setting member and said operating member and having both a reciprocatory and a rotatory movement, a vertical rod having both a reciprocatory and a rotatory movement, and a connection between said vertical rod and said operating rod, whereby said movements may be separately transmitted to said first-mentioned rod. 100 110

6. The combination, with a fare recorder having both a setting member and an operating member, of a single operating rod connected with both said setting member and said operating member and having both a reciprocatory and a rotatory movement, a vertical rod having both a reciprocatory and a rotatory movement, a horizontal rod interposed between said vertical rod and said first-mentioned rod, said vertical rod and said horizontal rod having their adjacent ends provided with an extension, a universal joint connecting said extensions with the respective rods, intermeshing gears connecting said extensions one with the other, a pivoted 115 120 125 130

bracket supporting said extensions and maintaining said gears permanently in mesh, said horizontal rod and said first-mentioned rod also having extensions at their adjacent ends and having universal joints connecting said extensions with the respective rods, intermeshing gears carried by said extensions, and a pivoted bracket to support said extensions and maintain said gears permanently in mesh, and means for imparting either a rotatory or a reciprocatory movement to said vertical rod.

7. The combination, with a fare recorder having both a setting member and an operating member, of a single operating rod connected with both said setting member and said operating member and having both a re-

ciprocatory and a rotatory movement, a second rod also capable of a reciprocatory and a rotatory movement and extending at an angle to said operating rod, each of said rods having an extension, universal joints connecting said extensions to the respective rods, intermeshing gears carried by said extensions and permanently in mesh one with the other, and a pivoted bracket having bearings for said extensions and maintaining said gears permanently in mesh.

In testimony whereof, I affix my signature in presence of two witnesses.

DAVID B. WHISTLER.
